UNITED STATES PATENT OFFICE.

THOMAS E. HENDERSON, OF FORT WORTH, TEXAS.

COLD PROCESS OF REPAIRING RADIATORS OF INTERNAL-COMBUSTION ENGINES.

1,340,655.

Specification of Letters Patent. Patented May 18, 1920.

Application filed November 22, 1919. Serial No. 339,859.

To all whom it may concern:

Be it known that I, THOMAS E. HENDERSON, a citizen of the United States of America, residing at Fort Worth, in the 5 county of Tarrant and State of Texas, have invented certain new and useful Improvements in Cold Processes of Repairing Radiators of Internal-Combustion Engines, of which the following is a specification.

10 My invention relates to a process of repairing breaks in radiator pipes in internal combustion engine equipment; and the object is to provide a process of repairing the breaks in radiator pipes, usually caused by 15 freezing, by which process the breaks can be quickly and efficiently repaired at very small cost; and one advantage is that the process is a cold process so that no time is lost in heating and preparing for heating and the 20 process is simple and inexpensive. Other objects and advantages will be fully explained in the following description and the invention will be more particularly pointed out in the claims.

25 Reference is had to the accompanying drawings for illustration of the process.

Figure 1 is a diagrammatic view, showing some broken radiator pipes and apparatus for depositing the repairing material. Fig. 30 2 shows one form of a discharge pipe or nozzle.

Similar characters of reference are used to indicate the same parts throughout the several views.

35 The repairing material includes two kinds of powdered metal and a binder liquid for making a composition of semi-liquid consistency. This composition is prepared in very small quantities,—one-half ounce being 40 usually sufficient, and there might be use for less than a half ounce. If more is prepared than for immediate use it will be lost because it would become set or solid and useless and cannot be revived.

45 If the radiator has much dirt or grease accumulated thereon it will have to be cleaned before repairing. This may be done by placing the radiator in a vat of boiling water and keeping the water boiling until 50 the radiator is cleaned. The radiator may be cleansed with acids, but the acid should be cleansed with water before repairing with the composition. The breaks in the pipes are detected in the pipes by water 55 tests, that is, by immersing the radiator in

water after closing all the connection openings except one for admission of air, and then forcing air into the radiator while under water. The breaks may be indicated by suitable marks or something attached to 60 the pipes at the points where there are breaks.

The composition is prepared by taking the required quantities of the two powders and mixing with the binding liquid until the 65 composition is of semi-liquid consistency. A small jar 1, adapted to contain about one-half ounce, is provided and the composition placed therein by removing the screw cap 2. A depositing or discharge nozzle 3 is carried by the top 2. The material or composition is forced out of the jar in a continuous stream through the nozzle by compressed air. This may be done by a pipe connection 70 4 which is also carried by the screw cap 2. 75 A hand rubber bulb 5 of rubber of ordinary type which is provided with an intake check valve 6 may be used to compress air on the composition to force the same through the nozzle 3. For depositing the composition 80 on the back side of a pipe, a nozzle 7 provided with a curved tip 8 may be used. Sufficient air may be compressed by hand for forcing the composition through the nozzle in a continuous stream until the required 85 amount is deposited on the break to be repaired. The material or composition is spread on the broken part to sufficient depth and allowed to set or become solid.

The composition can not be successfully 90 used where leaks occur, caused by violence, friction, vibration, or any corrosive agency in the upper or lower water pans, hose connections, or the connection of the core of the radiator with the upper or lower pans, 95 but is highly successful in repairing the breaks in the radiator pipes, as shown by actual service in repairing a number of radiators.

The nozzle 7 has an enlarged tapering end 100 8 which is inserted in a socket 9. The object of the tapering end is to make a connection which may be kept rigid in the socket by taking up wear. As the end wears, it may be tightened by forcing the end farther in 105 the socket to make it rigid.

The powders used may be varied. I have used successfully bronze powders and aluminium powders and the quantities may be varied as required for different purposes. 110

Enough lacquer is used to make a composition that is easily forced through the depositing devices.

What I claim, is,—

- 5 1. A cold process of repairing motor radiators consisting of mixing two kinds of powdered metal and a binder liquid, projecting the mixture on the parts to be repaired, and allowing the object to remain stationary until the mixture is set or dried.
- 10 2. A cold process of repairing motor radiators consisting of mixing two kinds of powdered metal and a binder liquid in a small receptacle provided with a depositing nozzle, projecting the mixture by compressed
- 15

air on the parts to be repaired, and causing the parts to remain stationary until the mixture has become dry or set.

3. A cold process of repairing motor radiators consisting of mixing two kinds of powdered metal and a binder liquid in a small receptacle provided with a depositing nozzle, projecting the required amount of the mixture by compressed air through said nozzle in a continuous stream on the parts to be repaired, and causing the parts to remain stationary until dry or set.

In testimony whereof I set my hand, this 8th day of January, 1919.

THOS. E. HENDERSON.
